UNITED STATES PATENT OFFICE.

GEORGE R. MEYERCORD, OF CHICAGO, ILLINOIS.

TOILET INCLOSURE OR BOOTH.

1,226,684.

Specification of Letters Patent.

Patented May 22, 1917.

Application filed May 31, 1913. Serial No. 770,838.

To all whom it may concern:

Be it known that I, GEORGE R. MEYERCORD, a citizen of the United States, residing at Chicago, county of Cook, State of Illinois, have invented a certain new and useful Improvement in Toilet Inclosures or Booths, and declare the following to be a full, clear, and exact description of the same, such as will enable others skilled in the art 10 to which it pertains to make and use the same, reference being had to the accompanying drawings, which form a part of this specification.

It is common practice to construct a toilet inclosure or booth of marble slabs, but there 15 is an objection to all such constructions in that exposed metallic hardware is required for fastening the parts together and, in the case of partitions or walls held clear of the 20 floor, exposed metallic supporting standards are required.

The exposed hardware requires constant 25 attention to keep it clean and, even when the greatest care is exercised, the hardware becomes unsightly and more or less unsanitary in time.

The object of my invention is to produce 30 a toilet inclosure or booth made of sanitary slabs and having no exposed metal fastening or supporting means and having the continuity of its surfaces uninterrupted so that it may at all times be kept easily in a clean and sanitary condition.

The various features of novelty whereby 35 my invention is characterized will hereinafter be pointed out with particularity in the claims; but, for a full understanding of my invention and of its object and advantages, reference may be had to the following detailed description taken in connection 40 with the accompanying drawings, wherein:

Figure 1 is a perspective view of a two-compartment toilet inclosure arranged in accordance with a preferred form of my invention, portions of one of the walls being broken away in order more clearly to disclose the construction;

Fig. 2 is a horizontal section on an enlarged scale through a portion of one side and the front wall of one of the compartments; and

Fig. 3 is a perspective view of the framework of the inclosure.

In accordance with my invention I build

up a skeleton supporting frame of the size and shape which the booth or inclosure is to have and then cover the frame with sanitary slabs or panels which serve both as the walls of the booth or inclosure and completely to conceal the supporting frame. 60

My invention may take various specific forms and may be employed in the construction of booths or inclosures of various sizes and shapes and adapted for various purposes. In the drawings I have illustrated the invention as embodied in a two-compartment toilet inclosure and, for the sake of brevity I shall confine the detailed description to this specific construction, although 70 it will of course be understood that my invention is not limited to this particular use or to the particular structural details so illustrated and described.

In the arrangement shown in the drawings the inclosure is one adapted to be built against a wall and to be closed at the rear by the wall. The framework consists of two sides each of which may conveniently be made of three parallel upright angle 80 irons, 1, 2, and 3, secured in any suitable way to the floor and having their upper ends connected together by a horizontal angle iron, 4. The angle irons 1 are secured to the wall, the angle irons 3 form the front corners of 85 the two sides of the inclosure, and the angle irons 2 are placed between the members 1 and 3. The upper ends of the two angle irons 3 may be connected together by parallel horizontal pieces or angle irons, 5 and 6, 90 the member 5 being at the upper ends of the members 3 and the members 6 being at such a height as to form the top of the door openings in the front of the inclosure. Extending down from the members 6 to the floor 95 are two pieces or angle irons, 7, lying parallel with the members 3 and each forming one edge of one of the door openings. Each of the members 7 is preferably connected across to the corresponding corner angle or post by 100 means of short pieces, 8 and 9, arranged respectively near the top and at the bottom. Midway between the members 7, and lying in the same plane, are two upright pieces or angle irons, 10, connected at their upper 105 ends to the cross piece 6 and at their lower ends to the floor; the members 10 being spaced apart a distance approximately equal to the width of the panel between the two door openings. The members 10 may be 110

connected together at the top by a cross piece, 11, and at the bottom by a cross piece, 12. Two other cross pieces, 13 and 14, are arranged between the members 10 at a distance apart equal to the height of the partition wall between the two compartments, the member 14 being at a distance above the floor approximately equal to the height above the floor of the lower end of the partition wall in the finished structure. The framework for the partition wall may conveniently consist of two horizontal angle irons, 15 and 16, resting at their front ends respectively on the cross pieces 13 and 14 and secured in any suitable manner at their rear ends to the wall against which the inclosure is built; together with an upright piece or angle iron, 17, extending between the members 15 and 16 and secured at its ends to these members midway between the ends of the latter.

The entire framework heretofore described, whether built of angle irons or other structural iron is cheap and simple, requiring only ordinary commercial metal cut in the desired lengths; and it is easily set up or assembled, since the various members may be rigidly connected together either by small rivets or simple stove bolts. In other words, the frame is built entirely of commercial iron which is simply cut into the proper lengths, drilled or punched and then fastened together with bolts or rivets.

While I have referred to the members 2 and 17 as being angle irons, these members are preferably made in the form of channels to give added strength.

After the skeleton frame has been set up it is sheathed, preferably with ordinary plaster board cut in panels of the proper size and shape and fastened in any suitable way upon the framework. In the arrangement shown, see particularly Fig. 2, the plaster board in each of the side walls is made in the form of two panels, 18 and 19, of a width to fit between the members 2 and 3 and the members 1 and 2, respectively, and of a height adapted to extend from the floor to the top pieces 4. The sheathing may be riveted to the members 1 and 3 or be tied thereto with wires. The sheathing may be fastened to the members 2 in any suitable way, conveniently by placing on the members 2 U-shaped clips, 20, having the free ends of their arms bent laterally as indicated at 21; the sheathing being laid against the bent ends 21 and a pin or nail, 22, being inserted through each clip and the body of the member 2 on the opposite side of the sheathing. The skeleton frame for the partition wall may be sheathed in the same way as the sides. The panels of the front of the inclosure, that is the panels at the sides and between the two door openings and across the top thereof may be sheathed by placing be-

tween the frame members of these panels suitable pieces, such as indicated at 23 in Fig. 2 and wiring or otherwise fastening them in place.

After the frame has been sheathed it is covered on both sides with plastering as indicated at 24 and 25 in Fig. 2. The combined thicknesses of the sheathing and the two layers of plastering are equal to or slightly greater than the width of the angle irons or channel irons so that after the plastering is completed, the sides, front and partition wall of the inclosure are smooth and continuous and of uniform thickness.

The whole is then sheathed with the sanitary slabs or panels, preferably the white glass known as "vitrolite". In the arrangement shown each side of the inclosure is sheathed on the inside and outside with two large panels, 26 and 27, extending from the top to the floor. Each side of the partition wall is similarly sheathed with panels, 28 and 29. The front is sheathed with suitable panels, 30, 31, 32 and 33. The result is that in the finished structure there are no exposed fastening means and every wall is smooth and continuous from one edge to another and has no projections corresponding with the usual hardware; so that there is no hardware to keep clean or to form with the sanitary panels cracks or crevices in which dirt can collect.

The finishing panels may be fastened in place in any suitable way, preferably by cementing them to the plastering with suitable layers of cement, as indicated at 35 and 36.

It is desirable to have the door jambs, where doors are employed, made of wood, since wood acts as a cushion and protects the more rigid structure against jars due to slamming the doors. The door jambs may conveniently be secured in place as illustrated in Fig. 2, 40 representing a door jamb lying against the angle iron, 7, and fastened thereto by suitable small bolts, 41, the adjacent finishing panels being made wide enough to overlap the door jamb slightly.

I claim:

1. A booth or inclosure comprising four upright corner angle irons, intermediate uprights of structural iron, transverse members connecting the uprights together, plaster board of less thickness than the width of said angle irons arranged between and secured to corresponding flanges thereof to form a solid wall, plaster supports on opposite sides of said plaster board of a thickness sufficient only to conceal the metallic structure, and sanitary slabs or panels cemented on both sides of the walls and wholly concealing the plaster.

2. A booth or inclosure open at the top, comprising upright corner angle irons, intermediate uprights of structural iron, transverse members connecting the uprights to-

gether, plaster board of less thickness than the width of said angle irons arranged between and secured to corresponding flanges thereof to form solid walls having free upper edges, plaster on opposite sides of said plaster board of a thickness sufficient only to conceal the metal structure, and sanitary slabs or panels cemented on both sides of the walls and extending from the free top edge

of the same to the bottom and wholly concealing the plaster.

In testimony whereof, I sign this specification in the presence of two witnesses.

GEORGE R. MEYERCORD.
